CLAIR S. REED, OF JACKSON, MICHIGAN, ASSIGNOR TO REYNOLDS SPRING COMPANY, OF JACKSON, MICHIGAN, A CORPORATION OF MICHIGAN

CUSHION SPRING STRUCTURE

Application filed September 28, 1931. Serial No. 565,572.

My invention relates to cushion spring structures to be used in conjunction with automobile seats and backs.

An object of the present invention is to provide a spring structure which embodies rows of coiled springs each of which includes a lower compressed spring formed from relatively heavy gauge wire and an upper spring formed of light gauge wire together with an envelope or casing for each row of springs that serves to eliminate noise and at the same time hold the springs under the desired compression.

A further object of the invention is to provide a cushion spring structure wherein the casing or envelope is formed from flexible material and so assembled with the springs as to maintain them under the desired compression.

The invention further provides a cushion spring structure embodying a plurality of spring units each of which includes a flexible casing in which the cushion springs are housed, the units being such as to permit any number of them to be assembled together to produce a cushion of desired size.

With the preceding and other objects and advantages in mind the invention consists in the novel construction, arrangement of parts and operations to be hereinafter specifically referred to, claimed and illustrated in the accompanying drawings, wherein—

Figure 1 is a top plan view having parts broken away of a cushion spring structure constructed in accordance with my invention;

Fig. 2 is a side elevation of the same;

Fig. 3 is a fragmentary bottom plan view;

Fig. 4 is a fragmentary vertical sectional view; and

Fig. 5 is a modification of the invention.

Referring to the invention in detail, a pair of rectangular frame members 5 and 6 arranged one above the other in parallel relation is provided. The frame members 5 and 6 are connected together by diagonally extending brace rods 7 which are connected to the rear side of the uppermost frame member and to the front side of the lowermost frame member by the usual clips 8.

The invention provides a plurality of spring units of identical construction. Each of these units consists of a flexible envelope or casing 10 formed from a single length of burlap or other suitable material. The casing or envelope 10 is formed with circular pockets or cells 11 which are produced by vertical rows of stitching 12 at spaced intervals. Arranged in the lower end of each of the cells or compartments is a coil spring 13 formed of relatively heavy gauge wire while a second coil spring 14 formed of light gauge wire is superimposed upon the spring 13 at the upper end of each cell or compartment. The upper springs 14 serve to provide a soft and pliant top surface while the bottom springs provide a relatively stiff and less resilient bottom which will absorb most of the vibration and not transmit the same to the upper springs.

In order to maintain the springs 13 and 14 under the necessary compression, so that they will be independent in action, each cell or compartment is drawn or gathered inwardly to provide an intermediate wall 15 of double thickness between the adjacent ends of the springs 13 and 14 and secured by a longitudinally extending stitch 16 which extends from one end of the casing or envelope to the other. The free edges of the casing or envelope are brought together at the center of the upper springs and stitched together as at 17. It will be manifest that the springs 13 will be maintained under compression by the bottom walls and intermediate wall 15 of the cells while the upper springs will be kept under compression by the intermediate wall 15 and the upper walls of the cells.

In practice any desired number of the spring units are arranged within the confines of the frame members 5 and 6 and the outermost springs are secured to these frame members by the usual securing rings 18.

In order to hold the parts together the springs 13 and 14 are secured together by suitable rings 19.

To further lend rigidity to the structure transverse brace rods 20 are secured to the front and rear of the lower frame member 6. The lower ends of the springs 13 at either

side of the brace rods 20 are secured together by rings 21 which embrace these rods as shown in Figure 3.

In the modification disclosed in Figure 5, 5 single springs 22 of relatively heavy gauge wire are arranged in the outermost pockets 11 to render the structure more rigid around its edges.

What is claimed is:—

- 10 1. In a cushion spring structure, a frame, a flexible casing supported thereby and having rows of pockets therein, each having a flexible intermediate partition, relatively heavy gauge springs confined in the pockets 15 between the partitions and bottom walls thereof, a light gauge spring in each pocket and arranged between the partition and upper wall thereof, the partition and upper and lower walls of the compartments serving to maintain the springs under compression.
- 20 2. As an article of manufacture, a spring unit consisting of a flexible housing formed with a plurality of longitudinally aligned pockets, expandable springs of different gauge 25 wire arranged in each pocket, and a flexible intermediate wall extending transversely of each pocket and disposed between the springs.
- 30 3. As an article of manufacture, a spring unit consisting of a flexible casing having a plurality of spring compartments therein, expandable springs of different gauge wire arranged in each compartment, and means for securing opposite walls of the casing together at a point between the opposed ends of the springs.
- 35 4. As an article of manufacture, spring cushion units each consisting of a flexible casing having top, bottom and side walls, the side walls being secured together at spaced intervals to provide vertically extending 40 pockets, relatively heavy gauge expandable springs arranged in the bottom of each pocket, lighter gauge springs arranged in the 45 pockets above the first mentioned springs, the side walls of the casing being drawn inwardly between the opposed ends of each pair of springs and secured, all of the springs being maintained under compression.
- 50 5. As an article of manufacture, a spring unit comprising fabric having the free edges stitched together to form a closed casing, the lateral walls being drawn inwardly and secured together to form a partition dividing 55 the casing into two pockets, and coil springs mounted respectively in said pockets.

In testimony whereof I affix my signature,
CLAIR S. REED,
